Patented Sept. 20, 1921.

FIG. 1.

FIG. 2.

FIG. 3.

INVENTOR:
George L. Lockhart.
BY his ATTORNEY:
A. M. Carlson.

UNITED STATES PATENT OFFICE.

GEORGE L. LOCKHART, OF ST. PAUL, MINNESOTA, ASSIGNOR TO L. P. T. SPECIALTY COMPANY, OF MINNEAPOLIS, MINNESOTA, A CORPORATION OF MINNESOTA.

GYMNASIUM-LIGHT.

1,391,550.

Specification of Letters Patent. Patented Sept. 20, 1921.

Application filed July 24, 1919, Serial No. 313,131. Renewed August 3, 1921. Serial No. 489,591.

To all whom it may concern:

Be it known that I, GEORGE L. LOCKHART, a citizen of the United States, residing at St. Paul, in the county of Ramsey and State 5 of Minnesota, have invented a new and useful Gymnasium-Light, of which the following is a specification.

This invention relates to protected lights in walls and especially in ceilings of gymnasiums and other rooms designed for playing of ball games and other games which are apt to damage lamps and lights protruding into the room. The object is to 10 so place and protect the lights by novel 15 means that they are safe from said dangers of getting broken.

In the accompanying drawing, Figure 1 is a face view of a light ready to be mounted in a wall or ceiling by my improved means. 20 Fig. 2 is a diametrical vertical section of Fig. 1 with the adjacent parts of a wall or ceiling also in section. Fig. 3 is a perspective view of the device detached from the ceiling and the members of it partly separated.

Referring to the drawing by reference numerals, and referring for shortness to the portion of the room as the ceiling (although the invention is applicable also to walls and 30 floors), 4 designates a portion of a concrete ceiling of a room used for ball playing and other athletic sports. Of said ceiling 5 designates the lath, 6 the plastering and 7 a conduit for electric wires (not shown) extending to a lamp 8, which may have an X-ray reflector 9. Said lamp is mounted in the top of a sheet metal box 10, which is molded into the concrete and has its lower edge formed with an outward flange 11, to 35 stiffen it and preserve its form.

Partly telescoped upwardly into the box 10 is a second box or frame, 12, having an external shoulder 13 stopping against the flange 11. Fixed to said shoulder is a low sheet metallic molding, 14, which is provided with holes for screws, or nails, 15, which engage in wooden strips 16, which

are molded into the concrete; or if the ceiling is not made of concrete they may be nailed to the regular ceiling joists.

Secured within the hollow molding 14 are nuts 17 for screws 18 to engage in and hold stops 19 within a recess 20 of the molding 14.

Supported upon said stops 19 is a heavy 55 wire netting 21; and upon said netting rests the outer flange 22 of a third frame, 23, which resembles in form an inverted metallic tray and has a comparatively large central aperture, 24, which is covered by a glass lens 25, held in place by fixed fingers 26. The corners of the frame 23 are provided with smaller apertures, 27, for the circulation of air.

When the parts are assembled for use, as 65 in Fig. 2, the molding 14 aids in deflecting flying balls away from the lights as a whole; and if a ball should be so directed that it strikes within the said molding, the netting 21 will protect the lens 25; and if the netting should ever permit the ball to reach the lens, the latter will aid in protecting the lamp proper. A further object of the lens is to give the desired color and dimness to 70 the light, as is indicated by the circular 75 waves 28 and radial ridges 29 in Fig. 1.

What I claim is:

1. The combination with a wall, ceiling, or other part of a room, having a cavity in its inward side, of a sheet metal box secured 80 in the cavity, an electric lamp mounted in said box, an open frame inserted upwardly partly into the box and having a molding projecting outwardly upon the face of the wall or ceiling about the cavity, and means 85 for securing said molding in place; said molding having an internal recess, stops detachably secured in said recess, a wire netting retained by the stops, a skeleton frame retained by the wire netting, and a glass 90 lens held by the skeleton frame intermediate the netting and the lamp.

2. The structure specified in claim 1, the outer edges of the skeleton frame filling be-

tween the netting and the internal shoulder that terminates the depth of the recess.

3. The structure specified in claim 1, the outer edges of the sheet metal box being 5 formed into an outward flange fitting against the external shoulder formed by the recess in the molding.

4. The structure specified in claim 1, said means for holding the molding to the wall 10 or ceiling comprising a wooden strip secured in said part of the room and nails or like

means passed through the molding and engaged in the wooden strip.

5. The structure specified in claim 4, said ceiling being formed mainly of concrete and 15 said strips being molded into the concrete.

6. The structure specified in claim 1, said lamp and lens being disposed in the cavity beyond the face of the wall or ceiling.

In testimony whereof I affix my signature. 20

GEORGE L. LOCKHART
